C. A. Snow & Co.

UNITED STATES PATENT OFFICE.

WALTER TELL O'NEIL, OF ETNA MILLS, CALIFORNIA, ASSIGNOR OF ONE-HALF TO BERT DUNN, OF SAME PLACE.

APPARATUS FOR CLEANING AND FLUSHING WASTE-PIPES.

SPECIFICATION forming part of Letters Patent No. 655,888, dated August 14, 1900.

Application filed February 6, 1900. Serial No. 4,198. (No model.)

To all whom it may concern:

Be it known that I, WALTER TELL O'NEIL, a citizen of the United States, residing at Etna Mills, in the county of Siskiyou and State of California, have invented a new and useful Sink, of which the following is a specification.

This invention relates to drains for sinks, bath-tubs, and similar articles which are subject to stoppage from solid matter that passes into the drain-pipe when the stopper is removed to permit drainage; the object of the invention being to provide a structure which may or may not be adapted for the reception of a stopper and which will permit the attachment of a hose with a water-tight joint, so that water or other fluid may be forced into the drain-pipe and the stoppage may be forced through the pipe in the usual manner. As drain-pipes of this nature are usually constructed a special instrument is required for forcing out the obstruction, and, furthermore, much difficulty is experienced in securing a water-tight or air-tight joint, which is necessary for an efficient flushing operation.

With the present invention the ordinary garden-hose may be connected with the drain-pipe and may be employed for flushing the drain-pipe with either hot or cold water from the ordinary spigot; also, a hose may be connected in an efficient manner from a pump or other source of pressure.

In the drawings forming a portion of this specification, and in which similar numerals of reference designate like and corresponding parts in the several views, Figure 1 is a view, partially in section and partially in elevation, showing the present invention applied to an ordinary washbowl or sink and illustrating the method of attachment of the flushing-hose. Fig. 2 is a section showing the upper portion of the drain-pipe and adjacent portions of the sink or bowl and illustrating the position of the stopper when substituted for the flushing pipe or hose.

In the drawings herewith the invention is shown as applied to an ordinary washbowl or sink, which is indicated at 5 and at the lowermost point of which is a drain-opening 6. The drain-pipe comprises an uppermost section 7, the exterior of which is of usual

form, and is provided with a radial flange 8 at its upper end, which rests in a depression 9 in the inner face of the bowl and concentric with the drain-opening 6.

Upon the exterior face of the pipe-section 7 are formed threads 10, which extend below the bowl and with which is engaged a nut 11, having a flange 12 at its upper end, and which nut is adapted for adjustment upon the threads 10 to clamp the bowl firmly between the flanges 8 and 12, and thus hold the drain-pipe firmly in position. A waste-pipe 13 is secured to the drain-pipe 7 through the medium of threads or in any other suitable manner and is adapted to convey the contents of the bowl, which contents pass through the drain-pipe.

In the side of the drain-pipe 7 and at points in a common line circumferentially of the pipe are formed openings 14, which communicate with the overflow-drain 15, which leads from the overflow-openings 16, adjacent the rim of the bowl, these openings 14 being of the usual form and arrangement.

A suitable distance below the upper end of the drain-pipe 7 is formed an interior flange 17, the upper face 18 of which forms a seat to receive the plug or stopper 19, and the inner face of this flange is provided with screw-threads, as shown at 20, the usual guard-wires 21 being disposed against the lower face of the flange, as illustrated in the drawings.

It will be noted that the flange 17 is so situated as to form the seat 18 at a point to receive the plug 19 in the usual manner, so that the formation of the threads does not in any way affect the usual functions of the structure.

The threads 20 are of such form and arrangement as to receive the exteriorly-threaded member 22 of a hose-coupling, and, as illustrated in Fig. 1 of the drawings, these threads permit the attachment of the coupling member 22, which is in turn fixed to a hose-section 23, the shoulder 18 receiving the usual washer 24, which lies upon the flange 25 of the coupling member, and thus this coupling member may be manipulated to secure a firm connection between the hose and the drain-pipe and one which will effectually

prevent leakage during the operation of flushing.

From the above description it will be seen that a hose may be led from either the hot or cold water faucet in a house, and water may thus be supplied in either a hot or cold condition to effect the cleaning of the pipe.

While the construction is shown and above described as having an ordinary garden-hose attached thereto, it will of course be understood that the threads may be of a size to receive any other means of accomplishing the desired purpose and also that while the present structure is shown as adapted to receive a stopper it is not necessarily so formed.

Various changes in the specific structure shown may be made, and any proportions and materials that are suitable may be employed without departing from the spirit of the invention.

What is claimed is—

A sink having a drain-opening and an overflow-opening communicating with the drain-opening below the inner surface of the sink, and a drain-pipe disposed in the drain-opening, said pipe having an interior continuous flange forming a plug-seat at its upper face and having its inner periphery threaded to receive a hose, said pipe having openings therein below the flange and communicating with the overflow, and guard-bars disposed transversely of the pipe between the openings and the flange. 25

In testimony that I claim the foregoing as my own I have hereto affixed my signature in 30 the presence of two witnesses.

WALTER TELL O'NEIL.
